UNITED STATES PATENT OFFICE.

WILLIAM W. MACFARLANE, OF ELKINS PARK, PENNSYLVANIA.

SYSTEM OF COMMUNICATION.

1,370,333.

Specification of Letters Patent. Patented Mar. 1, 1921.

Application filed May 15, 1919. Serial No. 297,371.

To all whom it may concern:

Be it known that I, WILLIAM W. MACFARLANE, a citizen of the United States, and a resident of Elkins Park, county of Montgomery, and State of Pennsylvania, have invented a certain new and useful System of Communication, of which the following is a specification.

The present invention relates generally to electric systems of communication and has for its main object to lessen the expense of installation of telephone systems and to transmit messages with audio frequency instead of radio frequency in wireless or semi-wireless apparatus.

In the accompanying drawing the invention is shown in a concrete and preferred form.

Each station is equipped with a local circuit 1 including a transmitter 2, a battery 3 and the primary winding 4 of a transformer. 5 is a secondary winding, the secondary windings of two stations being connected at one side only by a line conductor 6. 7 and 8 are helices constituting an intermediate winding and consisting of a copper strip say .016" x .5" wound on separate cores 9 and 10 and in series with each other, there being say twenty convolutions in each helix arranged in a single layer. Cores 9 and 10 are say $\frac{1}{16}$ " in diameter, and core 9 supports helix 7 and winding 4, while core 10 supports helix 8 and winding 5.

Winding 4 preferably consists of thirty five hundred turns of No. 28 wire, and winding 5 is preferably composed of one hundred and fifty thousand turns of No. 34 wire. All the proportions given are by way of explanation and are not intended as a limitation.

Receiver 11 has one terminal 12 connected to circuit 1 and the other terminal 13 extending at the outside of said receiver, and also in this form of the invention a conductor 14 connects each local circuit with the line conductor.

A voice current generated in circuit 1 of one station energizes the primary, intermediate and secondary windings thereof and is transmitted over conductor 6 to conductor 14 of the other station and thence over circuit 1 to receiver terminal 13 from which it presumably goes to the blind end of second-

ary coil 5 of the first station as indicated by the dotted lines and arrows. 55

This device will operate when blind ends of secondaries 5 are grounded and when terminals 13 are grounded. It has, however, been found possible to transmit messages when there is no ground as when the operator stands on a plate of glass and when blind ends of 5 are not grounded.

By the means described messages are transferred with audio frequency.

I claim:

1. A system of communication comprising: a plurality of sending and receiving stations, each station including a local circuit having a primary winding in series therewith, and a secondary winding in inductive relation to the primary winding, a line conductor connecting one side only of the two secondary windings, and a conductor connecting each local circuit with the line conductor independently of the windings. 75

2. A system of communication comprising: a plurality of sending and receiving stations, each station including a local circuit having a primary winding in series therewith, a secondary winding in inductive relation to the primary winding, and an intermediate winding in inductive relation to the primary and secondary windings, a line conductor connecting one side only of the two secondary windings, and a conductor extending around the several windings from the local circuit to the line conductor. 85

3. A system of communication comprising: a plurality of sending and receiving stations, each station including a local circuit having a primary winding in series therewith, a secondary winding in inductive relation to the primary winding, a line conductor connecting one side only of the two secondary windings, a conductor extending around the several windings from the local circuit to the line conductor, a transmitter having both sides connected with the local circuit, and a receiver having one side only connected to the local circuit. 95

4. A system of communication comprising: a plurality of sending and receiving stations, each station including a local circuit having a primary winding in series

therewith, a secondary winding in inductive relation to the primary winding, and an intermediate winding in inductive relation to the primary and secondary windings, a line conductor connecting one side only of the two secondary windings, and a conductor extending around the several windings from the local circuit to the line conductor, a

transmitter having both sides connected with the local circuit, and a receiver having one side only connected to the local circuit.

Signed at Philadelphia, in the county of Philadelphia and State of Pennsylvania this 9th day of May, 1919.

WILLIAM W. MACFARLANE.
